UNITED STATES PATENT OFFICE.

MATTHEW R. HULL, OF CONNERSVILLE, INDIANA, ASSIGNOR TO REX MANUFACTURING COMPANY, OF CONNERSVILLE, INDIANA, A CORPORATION OF INDIANA.

CONNECTING MEANS FOR TWO-PART AUTOMOBILE DOORS.

Application filed March 29, 1924. Serial No. 702,957.

To all whom it may concern:

Be it known that I, MATTHEW R. HULL, a citizen of the United States, residing at Connersville, in the county of Fayette and State of Indiana, have invented certain new and useful Improvements in Connecting Means for Two-Part Automobile Doors, of which the following is a specification.

My said invention relates to connecting means for a two-part door for automobiles or other vehicles and it is an object of the invention to provide a structure which shall be yielding and flexible and normally hold the demountable upper section of the door in a position such that the upper side and the closing side will tend to strike the frame of the door sooner than the other sides, i. e. it is biased toward the door frame and the vehicle body in this respect.

Referring to the accompanying drawings, which are made a part hereof and on which similar reference characters indicate similar parts,

Figure 1 is a partial elevation of the door taken from the inner side,

Figure 2 a detail of a connecting device viewed from the left in Figure 1, and

Figure 3 a section on line 3-3 of Figure 1.

In the drawings reference character 10 indicates the upper demountable section of an automobile door. Said section has a wooden frame 11 surrounding the sight opening and an overhanging fillet 12 for holding in place panels 13 and 14 of glass or other transparent material. The wooden frame has a pair of socket members 15 and 16 secured to its side members near their lower ends. The socket members are preferably formed of sheet metal and in a preferred construction each socket has one side part resting against the inside of the wooden frame member and secured thereto by screws or nails 17 while the other side rests against the outer side of the said frame member and is similarly secured thereto. A securing member in the form of a bent rod is shown at 18, said rod having a horizontal body portion, an upwardly-bent end extending into the socket of the member 15 and a downwardly-bent end projecting into a socket 19 on the permanent door section. Between said two sockets there is a bracket 20 fastened to the upper door section in any convenient manner as by means of a screw shown at 21 and a rivet at 22. The bracket

has a longitudinal opening or recess to receive the body of the rod 18 and the door sections are connected in a substantially rigid manner at the hinge side of the door by means of this rod.

A resilient rod 23 extends along the lower edge of the demountable section and upward into the socket 16. This member has an eye at the end farthest from said socket through which a nail or screw 24 can be driven into the wooden frame, said device also passing through an eyelet at the end of the bracket 20. The rod has pivotally mounted thereon intermediate its length a pin 25 adapted to extend downward into a socket in the permanent door section, which pin also slides on the rod. Normally the rod 23 stands in the position indicated in Figure 3, that is, the bent upwardly extending end hangs to one side so that when the bent end is inserted in the socket and the other is fastened in the position shown the body of the rod will be twisted and will act torsionally to throw the upper side and the closing side of the demountable section toward the door frame thereby insuring a close fit and absence of rattling or rumbling noise on the road due to imperfect contact between the door and the door frame. From the foregoing it will be seen that all that is necessary for removing the demountable section is merely to lift it off thereby removing the pin 25 and the lower end of the rod 18 from the sockets in the permanent section.

It will be obvious to those skilled in the art that changes may be made in the device of my invention without departing from the spirit thereof and therefore I do not limit myself to what is shown in the drawings and described in the specification but only as indicated in the appended claims.

Having thus fully described my said invention, what I claim as new and desire to secure by Letters Patent is:

1. In a two-part door for vehicles, a lower permanent section, an upper demountable section, means for securing the upper section detachably to the lower one at the hinge side, a bent torsion rod having a vertical arm projecting into a socket on the upper door section the body of said rod extending along the lower side of said section and secured thereto at its far end the relation of the arm to the body being such as to bias the upper and closing sides of the demount-

able section toward the frame, and a connection between said body and the permanent door section near the closing side of the door, substantially as set forth.

5. 2. In a two-part door for vehicles, a lower permanent section, an upper demountable section, means for securing the upper section detachably to the lower one at the hinge side, and independent means adjacent the closing side of the door biasing said demountable section toward the door-frame at its upper and closing sides, substantially as set forth.

10. 3. In a two-part door for vehicles, a lower permanent section, an upper demountable section, a bent rod at the hinge side of the door having a part underlying the demountable section and parts angularly related thereto respectively extending up into a socket on said section and down into a socket 15 on the permanent door, and an independent resilient connector near the closing side of the door securing the upper section to the lower and biasing the upper section toward closing position at its upper and closing 20 edges, substantially as set forth.

25. 4. In a two-part door for vehicles, a lower permanent section, an upper demountable section, means for securing the upper section detachably to the lower one at the hinge side, and a resilient connector near the closing side of the door securing the upper section to the lower and biasing the upper section toward closing position at its closing side, substantially as set forth.

30. 35. 5. In a two-part door for vehicles, a lower permanent section, an upper demountable section, means for securing the upper section detachably to the lower one at the hinge side, a connector rod having a flat end and an arm

40. at the other end at right angles to the body thereof adapted to be secured to the demountable section at the closing side the flat end having an eye to receive means for securing the rod to the under side of said demountable section, and means loose on the 45 rod for connecting it to the permanent door section between its ends whereby the body is under torsion when the upper door section is in place, substantially as set forth.

50. 6. A two-part automobile door comprising a permanent lower section, a demountable upper section, a resilient rod having an upright part secured to the upper door section and a body extending along the lower edge of said section, and means for securing the free end of said body to the upper door section in a twisted state to bias the upper end of said upper door section toward the vehicle body, substantially as set forth.

55. 7. A two-part automobile door comprising a permanent lower section, a demountable upper section, a resilient rod having an upright part secured to the upper door section and a body extending along the lower edge of said section, a guide for said body on the lower door section providing a fulcrum about which said body may be bent, and means for securing the free end of said body to said upper door section with said 60 body flexed to bias the free or closing side of said door section toward the vehicle body, substantially as set forth.

65. In testimony whereof, I have hereunto set my hand and seal at Connersville, Indiana, 70 this 25th day of March, A. D. nineteen hundred and twenty four.

MATTHEW R. HULL. [L. S.]
